Inventor—

James E. McDADE,
Tricker & DeBush,

Attorneys

UNITED STATES PATENT OFFICE

JAMES E. McDADE, OF CHICAGO, ILLINOIS

DEVICE FOR TEACHING DIVISION

Application filed January 2, 1930. Serial No. 417,851.

My invention relates to devices for teaching division and has for its object the provision of a new and improved means by the use of which a pupil can visualize readily the problem which he is required to do and can understand and appreciate the principles underlying the division process, and can get an understanding particularly with respect to remainders and the method of 10 computing them.

My device is preferably to be used for teaching short division, the device to be used by the pupil during the time when he is memorizing. The device is intended to 15 visualize the division operation, to be used for giving the pupil extended practice in doing division with the device before he is required to do such work abstractly without the device. When a pupil is taught, for 20 example, that 8 goes into 39 four times and seven over, it is hard for the pupil to understand what the teacher is talking about. Except as the pupil is enabled to understand the principle involved in the division, it is 25 very difficult for him to memorize or familiarize himself with all of the various combinations involved in ordinary short division.

It is the object of my invention to provide 30 a device which shows clearly just what the process of division is for giving the pupil the proper background with respect to long division to be studied later. It is one of the objects of my invention to provide means 35 of this type which can be produced very readily at a minimum of expense, the device being preferably such as to be convenient to use and convenient to store or handle. It is another object of my invention to improve 40 devices of this type in sundry details hereinafter pointed out. The preferred means by which I have accomplished my several objects are illustrated in the drawings and are hereinafter specifically described. That 45 which I believe to be new and desire to cover by Letters Patent is set forth in the claims.

In the drawings—

Fig. 1 is a face view of a card provided with a plurality of numbers arranged for 50 illustrating the process of dividing by 9;

Fig. 2 is a face view of a separately formed card to be used as a slider or finder in connection with the chart or table of Fig. 1 for solving problems in division;

Fig. 3 is a face view of the chart of Fig. 55 1 with the finder in position thereon for dividing 50 by 9;

Fig. 4 is a face view of a card similar to that shown in Fig. 1 but arranged for effecting division by 7; and

Fig. 5 is a view similar to Fig. 3 but showing a slightly different design and arranged for division by 11.

Referring now particularly to Figs. 1, 2 and 3, 10 indicates a card or sheet bearing 65 on its face a table of numbers from 1 to 90 arranged in rows both horizontally and vertically on the card, all of the numbers of the vertical row at the right of the table 11 as shown being multiples of 9, and the numbers 70 of each horizontal row in the form of device as shown being arranged in serially increasing order toward the right. Along the right-hand edge of the table, I have provided a series of numbers from 1 to 10 opposite the respective rows, such numbers 1 to 10 constituting a scale for cooperation 75 with an index as hereinafter pointed out for indicating the quotient in any desired division. The numbers of the several horizontal rows of the table all have equal horizontal spacing in the arrangement shown. The table as a whole is indicated by the numeral 11, and the row of figures at the right is indicated by the numeral 12.

For use in connection with the table 11 on the leaf 10, I have provided a slider or finder 13 in the form of a piece of cardboard or other suitable material of sufficient stiffness for convenient use. The upper edge 90 of the finder 13 is offset at an intermediate point to provide a shoulder 14, such shoulder 14 being of a width corresponding substantially to the vertical spacing of the numbers in the table 11. A star 15 is provided on the shoulder portion of the finder in such position as to be capable of being readily centered upon any one of the numbers of the table 11, such star 15 constituting an index 95 for enabling the user of the device to place 100

the finder in a predetermined critical position with respect to the selected number of the table 11. Upon the upper edge portion of the finder, extending from the shoulder 5 to the end of the device, I have provided a series of numbers arranged serially beginning with 1, such numbers having a spacing corresponding to that of the numbers in the horizontal rows of the table 11 and constituting a scale for cooperation with an index as hereinafter pointed out for indicating the remainder in any desired division. This row of numbers is indicated as a whole by reference character 16.

15 Whenever it is desired to divide any one of the numbers of the table 11 by 9, the finder 13 is placed across the table with the star 15 superposed upon the number next larger than the one to be divided. For example, 20 in Fig. 3, the star 15 is located above the number 51 for effecting a division of the number 50 by 9. The arrangement is such that the one of the numbers of the row 12 which is displayed on the table next above 25 the finder 13 indicates the quotient of the stated division, the upper edge of the finder constituting the index for such indication. The arrangement is such, further, that with the left-hand vertical row of numbers of 30 the table 11 serving as an index the scale 16 shows the remainder. It is thus seen that 9 goes into 50 five times and five over. The arrangement is such that, whenever the star 15 is placed on top of any one of the numbers of the table 11, for effecting a division 35 of the next smaller number, the number of the row 12 showing next above the finder 13 will indicate the quotient and that the number of the row 16 opposite the row at 40 the left-hand side of the table 11 will indicate the remainder.

When the pupil is required to divide 50 by 9 and carries out the process of division as above described by the use of the device, 45 he readily arrives at the solution as above described,—namely, five times and five over. With this information gathered from the use of the device, the pupil is enabled to see that there are five complete rows of numbers 50 of the table above the finder, each of such rows having nine numbers, and that there are five numbers of an additional row visible above the finder. In this way, he very readily understands not only that 9 goes 55 into 50 five times and five over but also how and why such is the case. That is to say, he understands readily the principle involved, wherefore he is enabled much more easily to do the necessary memorizing for 60 enabling him easily to handle problems of this type.

In the construction shown in Fig. 4, the arrangement is the same in all respects as that above described in connection with 65 Figs. 1, 2 and 3, except that the device is

arranged for division by 7 instead of for division by 9. In Fig. 4 the parts are indicated by the same reference characters as those above designated, except that the card is indicated by the numeral 17. The finder 13 shown in Fig. 4 is precisely the same as that shown in Figs. 2 and 3, or may be the same finder.

In the construction shown in Fig. 5, a card 18 is shown arranged for division by 11, such card being provided with numbers from 1 to 77 arranged in seven rows of eleven numbers each. In the construction shown in Fig. 5, the numbers of each row increase serially toward the left instead of toward the right as in Figs. 1 and 4. In view of this change of arrangement with respect to the numbers in the table, the slider device 19 has its remainder-indicating numbers also arranged in reverse order as compared with the finder 13, the remainder-indicating numbers being indicated as a whole by the numeral 20. In the construction shown in Fig. 5, the quotient indicating numbers at the right are opposite the lower portion of the top edge line, wherefore the series of quotient indicating numbers begins with zero opposite the first horizontal row of numbers on the table rather than with 1 as in Figs. 1 and 4. Such row of quotient indicating numbers is indicated by the numeral 21.

In the use of the construction as shown in Fig. 5, the star 15 is placed over the number next larger than the number to be divided, whereupon the quotient is indicated by the one of the numbers of the row 21 next above the upper edge of the finder 19, and the remainder is indicated by the number in the row 20 directly underneath the quotient indicating row. In the example illustrated, 11 is shown to go into 58 five times with three over. It will thus be seen that the device of Fig. 5 is perhaps more convenient for use as a dividing device than is the construction as shown in Fig. 1. The device of Fig. 5 is not, however, so clear as a device for teaching the principles of division and remainders as is the device of Fig. 1.

While I prefer to employ the construction as shown in Figs. 1 and 4, with other tables for division by correspondingly small numbers indicated on other cards, or with any desired number of such tables all shown on a single sheet, it is to be understood that my invention is not to be limited to the form shown in Fig. 1 except so far as the claims may be so limited by the prior art, it being understood that changes may well be made in the form and arrangement as illustrated in Fig. 5 or otherwise without departing 125 from the spirit of my invention.

I claim:—

1. In a device for solving a problem in division, the combination of a leaf member having on one face a table comprising a plu- 130

- rality of numbers arranged serially in rows in equally spaced position in one direction and arranged in rows in the cross direction, with the largest numbers in said first named 5 rows respectively successive multiples of a predetermined divisor, a finder having index means adapted readily to be placed over any selected number of said table for indicating the quotient of the number next 10 smaller than the selected number divided by said predetermined divisor, and a number displayed at a predetermined point with respect to the finder indicating said quotient.
2. In a device for solving a problem in 15 division, the combination of a leaf member having on one face a table comprising a plurality of numbers arranged serially in rows in equally spaced position in one direction and arranged in rows in the cross direction, with the largest numbers in said first named rows respectively successive multiples of a predetermined divisor, a finder member having index means adapted readily to be placed over any selected number of 20 said table for indicating the quotient of the number next smaller than the selected number divided by said predetermined divisor, index and scale means on said members respectively for indicating said quotient, and 25 index and scale means on said members respectively for indicating the remainder.
3. In a device for solving a problem in 30 division, the combination of a leaf member having on one face a table comprising a plurality of numbers arranged serially in rows in one direction and arranged also in rows in the cross direction, with the largest numbers in said first named rows respectively successive multiples of a predetermined 35 divisor, a finder member in the form of a card having a shoulder in its top edge for indicating the critical position of said member with respect to a selected number of said table for determining the quotient of said 40 number divided by said predetermined divisor, and scale means on one of said members adapted by reference to index means of the other member to indicate said quotient.
4. In a device for solving a problem in 45 division, the combination of a leaf member having a table thereon comprising a plurality of numbers arranged in rows both horizontally and vertically, with one of said 50 rows in one direction made up of multiples of a predetermined divisor and with all of the numbers in each of the rows in the cross direction differing from such multiple in said row by less than the value of said divisor, and a finder member comprising index 55 means for enabling the user to place the finder in predetermined critical position on said table with respect to a selected dividend on said table for indicating the quotient of 60 said selected dividend divided by said pre-
- determined divisor, said members comprising scale means on one member adapted by reference to index means on the other member to indicate said quotient.
5. In a device for solving a problem in 65 division, the combination of a leaf member having a table thereon comprising a plurality of numbers arranged in rows both horizontally and vertically, with one of said rows in one direction made up of multiples 70 of a predetermined divisor and with all of the numbers in each of the rows in the cross direction differing from such multiple in said row by less than the value of said divisor, and a finder member comprising index 75 means for enabling the user to place the finder in predetermined critical position on said table with respect to a selected dividend on said table for indicating the quotient of said selected dividend divided by 80 said predetermined divisor, said members comprising scale means on one member adapted by reference to index means of the other member to indicate said quotient and scale means on one member adapted by reference to index means of the other member to indicate the remainder.
